Application July 14, 1942, Serial No. 450,838

8 Claims. (Cl. 144—208)

1

The present invention relates to log turning apparatus for use in connection with bark removal operations, and more particularly to apparatus for periodically shifting the log rotationally upon a support whereby different successive longitudinal strip portions of the surface of the log are presented to the action of the bark removal means.

In the preparation of logs for use in pulp manufacturing processes, it is necessary first to remove the bark and other foreign matters from the outer surface thereof. Letters Patent No. 2,342,533, granted February 22, 1944, to Miles Lowell Edwards for Method of removing bark from logs, discloses a method of removing bark from logs by means of hydraulic jets which are moved longitudinally relative to the surface of the log. Depending upon the number of nozzles employed and the jet size, only a relatively narrow strip of bark can be removed from the log surface at each application of the jets to the log. It is necessary, therefore, in order to effect complete removal of the bark from the log, to pass the nozzles longitudinally of the log a plurality of times, removing different successive strips of bark at each time, until the entire outer log surface is cleaned. In order to effect the presentation of successive longitudinal strips of the log surface to the action of the hydraulic nozzles, means must be provided for effecting predetermined angular rotational movements of the log and for holding the log firmly in each successive position of adjustment.

It is a general object of the invention, therefore, to provide a new and improved log turning apparatus for periodically shifting a log rotationally upon a support, whereby different successive longitudinal strip portions of the outer surface of the log are presented to the action of bark removal apparatus mounted adjacent thereto.

It is a further object of the present invention to provide a new and improved arrangement for supporting a log in a predetermined position with respect to hydraulic bark removal jets and to provide means for effecting rotational adjustment of the log on the support, whereby different successive longitudinal strips thereof are presented to the action of the jets; and, further, for holding the log firmly in the adjusted position throughout the bark removing operations.

A further object of the invention is to provide a new and improved arrangement for so supporting a log as to present different successive longitudinal strips of the surface thereof to the

2

action of other surface treatment apparatus, including turning means for periodically shifting the log upon the support with a high degree of accuracy so that the entire circumferential surface of the log is exposed to the action of such surface treatment apparatus.

A further object of the invention is to provide a simplified log turning arrangement which is readily adaptable to logs of differing diameters without requiring any adjustment in accordance with the log size.

A further object of the invention is to provide a log turning apparatus which is capable of effecting rotation of logs upon a support through predetermined angular increments substantially irrespective of variations in diametric size of the logs and also irrespective of the cross sectional configuration thereof.

In accordance with the illustrated embodiment of the invention, the apparatus comprises a suitable support upon which a log may be loosely positioned. A plurality of uprights, or stops, are provided along one side of the log for limiting movement of the log upon the support in the direction of the stops. The turning means further comprises friction means which engages circumferentially with the surface of the log on the opposite side thereof with respect to the stops and which normally exerts a pressure thereagainst so as to hold the log firmly in engagement with the stops. In the specific arrangement shown, the friction means comprises one or more toothed chains which extend at right angles with respect to the axis of the log and which are so supported on suitable sprockets or rollers that a considerable length of the chain engages closely against a sector of the log circumference, thus conforming with the surface configuration of the log and bearing thereagainst with considerable contact pressure. A driving means is associated with the chain and which, upon periodic energization, exerts a circumferential thrust upon the surface of the log for rotating the log a circumferential distance equal to a strip of bark to be removed. The arrangement of the chains is such that proper frictional engagement is had with the surface of the log substantially irrespective of the diametrical size or variations in cross sectional configuration thereof. In the event that the chains in and of themselves may not be able to provide a sufficient rotational torque to the logs to effect proper adjustment thereof, an auxiliary arrangement comprising one or more nigger bars is arranged to be brought into engagement with the

underneath surface of the log in such a manner as to supplement the action of the chains.

For a consideration of what is believed novel and invention, attention is directed to the following description, taken in connection with the accompanying drawings, while the features of novelty will be pointed out with greater particularity in the claims appended hereto and comprising a part of the disclosure.

In the drawings, Figure 1 is a side elevation 10 of the log supporting and turning arrangement constructed in accordance with one form of the invention; Figure 2 is a plan view of the log turning arrangement shown in Figure 1; Figure 3 is an enlarged fragmentary view of one detail shown in Figure 1; Figure 4 is a cross sectional view taken along the line 4-4 of Figure 3; and Figure 5 is a plan view of the supporting bracket arms taken on the line 5-5 of Figure 1, the position of a log thereon being indicated by broken lines.

Referring to the drawings, a log indicated at 10 is shown resting upon a suitable horizontal support indicated generally at 11 in such a manner that a lower longitudinal strip portion 12 of the log surface is exposed to the action of a plurality of hydraulic jets directed thereagainst from nozzles 13 mounted on carriage 14. Water issuing from the nozzles 13 and impinging against the surface portion 12 of the log 10 acts thereupon with such force as to effect substantially complete removal of the bark therefrom. The nozzle carriage 14 may be moved longitudinally relative to the log along a horizontal straight line whereby a strip of bark is removed from the log throughout the full length thereof. After one strip of bark has been removed from the log it is then rotated upon the support 11 by means of a turning arrangement, indicated generally at 16, through a predetermined angle corresponding generally to the width of the strip of bark removed by one pass of the nozzles, and the nozzle carriage is again moved lengthwise relative to the log. By thus exposing successive longitudinal strip portions of the log surface to the action of the hydraulic jets issuing from the nozzles 13, the entire surface of the log may be cleaned of bark.

The specific design of the nozzles, the nozzle supporting carriage, and the necessary controls therefor form no part of the present invention, reference being made herein to our copending application, Serial No. 450,837, filed concurrently herewith, entitled Log barking apparatus, now issued as Patent No. 2,393,978, granted February 5, 1946, which describes in complete detail one suitable form of apparatus which may be utilized in conjunction with the log supporting and turning arrangement of the present invention. It is to be understood that the utility of the present invention is not necessarily restricted to use with such other apparatus alone.

The support 11 may be of any suitable type for holding the log 10 in a generally horizontal position. As shown, the log supporting arrangement comprises a plurality of similar bracket arms 18, it being understood that while only one bracket arm 18 is shown, a number of other similar arms are positioned in line therewith, or at least the upper surfaces thereof engaging with the underneath surfaces of the logs are in an aligned relation. The bracket arms 18 are terminated adjacent the point of bearing contact with the underneath surface of the log so as to expose the log surface portion 12 throughout the full length thereof to the action of the jets. Since

the upper surfaces of the various bracket arms are horizontally aligned, the lower log portion 12 exposed to the action of the hydraulic jets from nozzles 13 also lies in a substantially horizontally straight line, and the distance therefrom to the tips of the nozzles 13 is substantially uniform throughout the full length of the log, irrespective of the angle of taper of the log 10 or the sizes of different logs.

The log supporting arrangement also includes a plurality of stops or uprights 21 arranged along one side of the log. These stops act to limit the movement of the log laterally on the bearing surfaces of the supports 11. The stops 21 are preferably slidably mounted upon the bracket arms 18 for adjustment by means of screws 22 associated therewith, whereby compensation may be made in accordance with the size of the logs fed onto the support 11. It will be understood that the distance between the forward end of the bracket arms 18 and the stops should be adjusted in accordance with the diameter of the log in each case in order that the strip portion 12 of the log will overhang the forward ends of the bracket arms for presentation to the hydraulic jets. It will here be noted that the details of the log supporting mechanism 11, including the particular arrangement of the bracket arms 18, the adjustable stops 21, and the stop adjusting means, are separately described and claimed in our copending patent application, filed concurrently herewith, Serial No. 450,836, entitled Log barking apparatus, now issued as Patent No. 2,396,255, granted March 12, 1946. Insofar as the present invention is concerned, however, the particular details of the log supporting arrangement is relatively unimportant since the log turning means presently to be described is operative as a unit irrespective of the exact nature of the log supporting apparatus.

For periodically rotating the log 10 upon the support 11 through predetermined angular increments, in order that different successive longitudinal strip portions of the outer surface thereof may be presented to the action of the hydraulic jets issuing from nozzles 13 for effecting complete removal of the bark throughout the log circumference, the turning arrangement indicated generally at 16 is provided, and which, in the specific arrangement shown, is supported from a superstructure extending above the log and the supporting means therefor. In general, the log turning apparatus comprises means for frictionally engaging with the outer surface of the log 10 on the opposite side or sides thereof with respect to the stops 21 and the bracket arms 18. The friction means normally bears against the surface of the log with a considerable pressure so as to provide a complementary support for the log and hold it firmly in place upon the support 11 throughout one pass of the nozzles 13. Upon the completion of each pass of the nozzles, the friction means are energized through a suitable driving mechanism and cause the log to be rotated upon the support 11 a circumferential distance equal to the width of the strip of bark removed by one pass of the nozzles, thereby exposing a new surface strip of the log to the action of the hydraulic jets. While various forms of friction means will suggest themselves to one skilled in the art following a perusal of the instant disclosure, the specific form shown herein comprises a toothed chain 25 which is trained over a generally triangular arrangement of wheels 26, 27 and 28. The wheel 26 may be a

sprocket meshing with the links of chain 25 through which the chain may periodically be driven, while the wheels 27 and 28 may be merely idler rollers for positioning the chain relative to the surface of the log 10 and for tensioning the chain, respectively. The sprocket 26 is mounted upon an arm 29 pivotally mounted adjacent its upper end as at 31 on beam 32 of the superstructure. The sprocket 26 is adapted to be driven through a chain or belt 33, from a ratchet wheel 34 journaled upon the arm 29 adjacent the upper end thereof. The ratchet wheel 34 is rotated upon the energization of a suitable motor 35 such as a servo-motor, the piston rod 36 of which is connected to the outer end of an arm 37 pivoted coaxially with the ratchet wheel 34 and having a pawl 38 thereon for engaging with the teeth on the periphery of the ratchet wheel.

The idler wheel or sprocket 27 is journaled for free rotation upon the lower extremity of an arm 41, the upper end of which arm is pivotally connected as at 42 to the end of a second arm 43, which second arm is pivotally mounted as at 44 to a bracket 45 affixed to the superstructure beam 32. In the operative position of the chain 25 the sprocket 27 depends somewhat below the horizontal plane of the axis of the log 10 and relatively closely adjacent the log surface. The idler wheel 28 is journaled upon one end of an arm 47, the opposite end of which is pivotally mounted upon a suitable bracket 48 fixedly attached to the arm 41 toward the upper end thereof. An adjustable tension spring 49 is arranged between the free end of arm 47 and the upper end of the arm 41 for applying a suitable tension to the chain 25.

Journaled upon the lowermost end of the arm 29 is an idler roller 51 which bears against the upper surface of the chain 25 during its run between sprockets 27 and 26, urging it against the upper surface of the log 10 and, furthermore, acting as a support for the lower end of the arm 29 when the chain is in the operative or log engaging position.

It will be observed that the chain 25 extends at right angles with respect to the longitudinal axis of the log 10 and is wrapped around a considerable circumferential sector of the surface of the log 10 and in a closely engaging relation therewith. Irrespective of the exact surface configuration of the log and the diameter thereof, that portion of the chain between the wheels 51 and 27 will fit snugly against the outer surface of the log.

Attached to the lower end of the arm 41 is a cable 53 extending from a motor driven drum 54 suitably mounted as upon bracket 55, which cable is provided for hoisting the log turning mechanism to the inoperative position illustrated in dotted lines for permitting loading and unloading of logs onto the support 11. As arm 41 is raised, the chain 25 extending around the wheels 51 and 26 pulls the lower free end of the arm 29 upwardly. The cable 53 is also utilized for limiting downward movement of the arm 41 to substantially the position shown in full lines. With the arm 41 in the position shown, and with the wheel 51 provided on the lower extremity of the arm 29 resting upon the upper surface of the log 10, the log is held firmly in its position of adjustment upon the support. After the nozzle arrangement 13, 14 has made one pass, and one strip of bark has been removed from the log, the servo-motor 35 may be energized to rotate the ratchet wheel 34 through a predetermined

arc which in turn will cause a predetermined length of movement of the chain 25. By virtue of the frictional engagement of the chain 25 with the periphery of log 10, the log will be rotated in the counter-clockwise direction as viewed in Figure 1 a corresponding circumferential distance. The angle of movement is selected to correspond generally with the width of the strip of bark removed by the hydraulic jets during each pass of the nozzles.

It will be understood that as many chains 25 may be provided as are required, depending, of course, upon the length and size of logs to be handled thereby. In the plan view of Figure 2 is illustrated a layout including two such chains, though it is to be understood, of course, that either one, or more than two, may be provided as required. In the event that a plurality of chains are used, the operation of the servo-motors therefor may be synchronized by provision of a suitable control valve (not shown) of a type well known in the art so that the rotational forces exerted upon the log through their corresponding chains will coincide in time and extent of operation.

Frequently it happens that a log is not entirely round but has one or more flattened sides. As such a log is rotated upon supporting brackets, the flattened side bearing against either the straight side of the stop 21 or the upper bearing surface of the bracket arm 18 might interfere with the ready rotation of the log solely through the operation of the chains. For assisting the chains in effecting rotational adjustment of logs which are resting upon the supports with a flattened side against one of the bearing surfaces, there is provided one or more nigger bars 61 which are arranged beneath the log. The nigger bars 61, having a plurality of teeth 62 on the forward upper edge thereof, are pivotally mounted as at 63 upon the end of an operating arm 64, the opposite end of which is connected to the piston of a servo-motor 65 fixedly mounted upon a suitable support such as beam 66 of the substructure. Depending from the rear end of the nigger bar 61 is a counterweighted portion 67 having a foot 68 normally bearing against the adjacent surface of the upper end of the operating arm 64. The operating arm 64 for the nigger bar is provided with a squared section 71 arranged to slide in a bearing 72 mounted on the beam 73 for retaining the nigger bar in the upright condition as shown. Referring to Figure 3, a log 75 is shown mounted upon the bracket arm 18 and having a flat side 76 resting against the nose of the stop 21. The chains 25 (not shown in this figure) might not be able to exert a sufficient rotational force by virtue of their frictional engagement with the surface of the log to effect proper rotation thereof, and in such event the servo-motor 65 may be energized so as to cause upward movement of the arm 64 carrying with it the nigger bar 61. The forward end of the nigger bar will be moved upwardly into engagement with the lowermost surface of the log 75, tending to urge it upwardly off of the bearing surface of the bracket arm 18. By virtue of the chains 25 and the apparatus associated therewith bearing downwardly against the log tending to resist upward movement thereof, the nigger bar arm 61 will be caused to pivot about the bearing 63 simultaneously with movement in the upward direction to some such position as is illustrated in dotted lines. Movement of the nigger bar in this direction, however, will cause the lowermost

side of the log to be moved outwardly on the outer ends of the bracket arms 18, while the chains 25 will maintain the log 76 in engagement with the stops 21. The resultant effect will be one of angular rotation on the part of the log and a shifting of the flattened portion 76 away from the stop 21 to the dotted line position indicated at 76'. Thus, by the manipulation of one or more of the auxiliary boosters, such as the nicker bars just described, in conjunction with the chain arrangements, logs of virtually any cross sectional configuration, which may vary substantially from circular shape, or of any size, may effectively be rotated upon the support whereby the entire surface thereof may be presented to the action of the hydraulic barking nozzles for effecting a complete removal of the bark.

Having described the principle of the invention in what is considered to be an operative embodiment thereof, it is to be understood that the specific details shown are merely illustrative, and that the invention may be carried out by other means.

We claim:

1. In a log turning apparatus, support means for loosely holding a log in a generally horizontal position, stops extending along one side of said log for limiting movement of said log laterally in one direction upon said support means, a chain, a pivoted arm having a roller thereon for urging said chain against the side of a log opposite said support, a second pivoted arm having a roller thereon for urging said chain against the side of said log opposite said stops, said chain between said two rollers engaging the surface of said log for holding said log on said support means against forces created by the action of a log treating mechanism acting on said log, and means for driving said chain so as to rotate said log.

2. In a log turning apparatus, support means for loosely holding a log thereupon in a generally horizontal position, stops extending laterally of said support means to prevent lateral movement of said log in one direction, an endless chain, said support and said chain being positioned in opposite relation for holding a log on said support means against forces created by the action of a log treating mechanism acting on said log, a pair of rollers engaging with one side of said chain, means supporting said rollers for urging them against peripherally spaced points on the surface of a log opposite said support means, means tensioning said chain whereby the entire length of said chain between said two rollers is caused to contact closely with the periphery of the log between said two rollers, means for periodically driving said chain for causing rotation of said log on said support, and means for moving said roller supports and carrying said chain and said rollers away from said log.

3. In a log turning apparatus, support means for loosely holding a log thereupon in a generally horizontal position including stop means for limiting movement of the log in one direction laterally of said support, an endless chain, a plurality of rollers supporting said chain, a pair of rollers including at least one of said supporting rollers engaging one side of said chain for urging a length of the chain between said rollers into supporting engagement with a circumferentially extending portion of the surface of said log generally opposite the bearing surfaces of the said support means for holding said log firmly thereon, pivoted supports for each of said rollers, mo-

tor means for driving said chain for effecting rotational movement of said log, and means for moving said pair of rollers and said chain away from said log.

5. In a log turning apparatus, the combination comprising support means for loosely supporting a log in a generally horizontal position, stops extending along one side of said log for limiting movement of said log laterally in one direction upon said support means, a chain engaging closely around an arcuate circumferential portion of the log surface opposite said stops for holding said log firmly against said stops during operations performed on said log, means for holding said chain against said log at right angles with respect to the axis thereof, and motor means for periodically shifting said chain for effecting rotation of said log on said support means, booster means for engaging with the underneath surface of said log, means for moving said booster means at right angles to the longitudinal axis of the log, for assisting said chain in effecting rotation of said log on said support means.

5. A log supporting and turning apparatus comprising support means for engaging the underneath surface of a log at a plurality of longitudinally spaced points for partially supporting said log in a generally horizontal position thereupon and having means for limiting movement of a log laterally of said support means in one direction, a generally triangular arrangement of wheels mounted above and on the opposite side of said log with respect to said support means, an arm pivotally mounted adjacent its upper end on the superstructure of said apparatus and having one of said wheels journaled on said arm, a second arm pivotally mounted on said superstructure and having a second of said wheels journaled on said arm, said latter wheel depending somewhat below the horizontal plane of the axis of the log and closely adjacent the log surface, a toothed chain trained over said wheels, the run of said chain between said first and second wheels aforementioned being wrapped around a considerable circumferential sector of the surface of the log for holding said log on said support means, and means for driving said chain so as to rotate said log.

6. A log supporting and turning apparatus comprising support means for engaging the underneath surface of a log at a plurality of longitudinally spaced points for partially supporting said log in a generally horizontal position thereupon, said support means including means for limiting movement of a log laterally of said support means in one direction, a generally triangular arrangement of wheels mounted above and on the opposite side of said log with respect to said support means, an arm pivotally mounted adjacent its upper end on the superstructure of said apparatus and having one of said wheels journaled on said arm, a second arm pivotally mounted on said superstructure and having a second of said wheels journaled on said arm, said latter wheel depending somewhat below the horizontal plane of the axis of the log and closely adjacent the log surface, a toothed chain trained over said wheels, the run of said chain between said first and second wheels aforementioned being wrapped around a considerable circumferential sector of the surface of the log opposite said support means for holding said log on said support means, means for driving said chain so as to rotate said log, and means for raising said arms, wheels and chain to an inoperative position above said log for

facilitating lateral movement of said log during loading and unloading operations.

7. In a log turning apparatus, the combination comprising a support for loosely holding a log thereupon in a generally horizontal position and having means for limiting movement of the log in one direction laterally of said support, an endless chain, means engaging said chain and urging a length thereof into peripheral contact with the surface of the log opposite said support means for holding said log on said support during operations performed on said log, means for driving said chain so as to effect rotational movement of said log on said support, booster means arranged beneath said log, and means for moving said booster means in a direction at right angles to the longitudinal axis of the log and into engagement with the underneath surface of the log for assisting said chain in effecting rotational movement of said log on said support.

8. In a log turning apparatus, support means for loosely holding a log thereupon, stops extending laterally of said support means to prevent lateral movement of said log in one direction, a chain engaging a sector of the periphery of said log opposite said support means and providing a complementary support for holding said log securely against the forces created by a log treating apparatus acting on said log, a pair of spaced

rollers engaging with one side of said chain, means supporting said rollers against angularly spaced points on the circumference of said log, means for tensioning said chain between said two rollers, and means for driving said chain for causing rotation of said log on said support.

MILES LOWELL EDWARDS.
